(57) **CLAIM**

The ornamental design for a sprinkler head, as shown and described.

DESCRIPTION

FIG. 1 is a front elevational view of the sprinkler head of this invention, the rear elevational view is a mirror image thereof;
FIG. 2 is a right side elevational view thereof, the left side elevational view being a mirror image thereof;
FIG. 3 is a top plan view thereof;
FIG. 4 is a bottom plan view thereof;
FIG. 5 is an isometric view thereof; and,
FIG. 6 is another isometric view thereof, with environmental structure shown in broken lines and forming no part of the claimed design.
